UNITED STATES PATENT OFFICE.

CLYDE A. PECK, OF NEWTON, IOWA.

FIGURE TOY.

Application filed July 20, 1927. Serial No. 207,105.

My invention relates to toys with articulated parts.

More particularly it is my purpose to provide such a toy in which the body and limbs 5 may be made of a series of flat discs preferably of two sizes, successively pivoted together so that they will be frictionally held in any position to which they may be adjusted for thereby making it possible to give 10 to the toy a great variety of adjustments to different positions.

With this and other objects in view my invention consists in the construction, arrangement and combination of the various parts of 15 my device, whereby the objects contemplated are attained, as hereinafter more fully set forth; pointed out in my claims, and illustrated in the accompanying drawings, in which:

20 Figure 1 is a front elevation of a toy embodying my invention.

Figure 2 is a side elevation of the same.

Figure 3 is a detail sectional view taken 25 on the line 3—3 of Figure 1, showing the parts in position for shipment and storage; and

Figure 4 is another front elevation showing the toy adjusted to different position.

In my business, we find that we cut out a 30 great many discs which are of practically no value except as junk metal. It is possible in the manufacture of a toy herein under consideration, to utilize this otherwise waste metal to great advantage and therefore produce 35 a toy at a very modest cost.

In making this toy I preferably use two sizes of discs. In Figure 1 I have shown the discs 10 of the larger size riveted together 40 near their edges by means of rivets 12. The rivets 12 are put in by machine which is so adjusted that the rivets will be made just tight enough so that the discs may be swung on their pivots to a great variety of positions with relation to each other and will be 45 frictionally held in any of the positions to which they may be adjusted.

I have shown in my drawings, the figure of a man but it will be understood that figures of various kinds of animals may be 50 made.

For forming the limbs of animals I secure as for instance in making a leg, a plurality of smaller discs 14 successively to one of the discs 10 and to each other as shown in Figure

1, each disc being fastened to the next two 55 adjacent discs by means of rivets 12 such as have been referred to. As many of the smaller discs 14 are used as the length of limbs require. The arms are made in the 60 same way.

For feet I make the following provision:— One of the larger discs 10 is provided with a tongue 16 bent outwardly slightly from the plane of the disc 10. This tongue is pivoted to the outer, smaller disc 14 of the leg as indicated at A in Figure 1 or at A in Figure 2.

When manufacturing process has been completed, the foot disc 10 lies along side the outermost disc 14 in a plane parallel therewith. This makes a convenient arrangement for shipment or storage and leaves the completed toy substantially flat.

The legs L and arms B can be swung under the body portion of the animal so that the limbs are thus collapsed or folded into a 75 relatively narrow space. I preferably form a head 18 with a special die. The head can be painted or otherwise finished as may be desired. The head is secured to one of the discs 10 by means of a rivet 12, in the manner hereinafter described.

Where the toy represents an animal, the outermost discs 14 of the front legs are connected to discs 10 in the same manner as shown at A. When a human figure is made, 85 the outermost discs 14 are preferably provided with tongues 20 bent outwardly slightly from the bodies of the discs. These tongues 20 may be used for inserting certain articles such as a small toy tennis racket 22.

The outermost discs of the limbs may be provided with the tongues 20 in the animal figures so that for example, a cat may be made to hold the figure of a mouse or any 95 other article suitable for the purpose.

The whole figure can be folded in a very small space forming a substantially flat package and can be for storage or shipment. When the toy is taken from the package the 100 feet discs 10 are bent from the position parallel to the discs 14 to which they are pivoted by bending the tongues 16 until the feet discs 10 stand at right angles to the adjacent discs 14 as illustrated by dotted lines in Figure 3. The feet discs 10 will then support 105 the figure as shown in Figures 1 and 4.

The toy can be adjusted on its pivots to a

great variety of positions. In Figure 4 I have shown an adjustment of the toy shown in Figure 1.

It will be seen from the foregoing that I have produced a toy of very simple structure which can be made out of inexpensive material.

For a toy like the one illustrated, there are needed two sizes of discs some of which are 10 cut to provide the tongues 16 and 20 which would really mean four kinds of discs, a head and rivets. Such a toy can be made to represent camels, giraffes, cats or other animals each of which is capable of adjustment to a 15 great variety of positions for the amusement of children.

The discs should have sufficient resiliency so that the tongues 20 will have a gripping action on the member 22 or the like and 20 should be made of such material as to permit the bending of the tongues 16 for the adjustment of the feet discs 10.

I claim as my invention:

1. A figure toy comprising a head shaped disc, a plurality of flat discs forming a body and a plurality of smaller flat discs forming limbs, said discs being successively pivoted together whereby they are frictionally held in any position to which they are 25 adjusted whereby the body and limbs of the toy may be made of sheet metal punchings.

2. A toy comprising a series of flat substantially disc like members successively pivoted together to be frictionally held in any 30 position to which they are adjusted, the body of the toy being formed of larger discs and the limbs of smaller discs, said toy hav-

ing feet disc members having tongues cut from their central portions and pivoted to the outermost disc of the legs of the toy. 40

3. A toy comprising a series of flat substantially disc like members successively pivoted together to be frictionally held in any position to which they are adjusted, the body of the toy being formed of larger discs and 45 the limbs of smaller discs, said toy having feet disc members having tongues cut from their central portions and pivoted to the outermost disc of the legs of the toy, certain of said discs having tongues cut therefrom 50 for forming holding means.

4. A toy comprising a series of flat, substantially disc-like members successively pivoted together to be frictionally held in any position to which they are adjusted for forming a body and limbs, the body of the toy being formed of larger members and the limbs of smaller members, said toy having feet members arranged at right angles to the adjacent leg members and pivoted thereto 55 for being frictionally held in various adjusted positions.

5. A toy comprising a series of flat substantially disc-like members including larger members forming the body and head of a toy, the body and head members being pivoted together, and a series of pluralities of smaller disc-like members successively pivoted together to each other and to the body for forming the legs of a toy, the respective 60 discs being so pivoted that they may be frictionally held in any position to which they are adjusted.

CLYDE A. PECK.
